UNITED STATES PATENT OFFICE.

CHRISTOPHER BEHAN, OF LAPEER, MICHIGAN, ASSIGNOR, BY DIRECT AND MESNE ASSIGNMENTS, TO JAMES DONOVAN AND S. HORACE ROBERTS, OF THREE RIVERS, MICHIGAN.

CATTLE-GUARD.

SPECIFICATION forming part of Letters Patent No. 793,977, dated July 4, 1905.

Application filed August 23, 1904. Serial No. 221,848.

To all whom it may concern:

Be it known that I, CHRISTOPHER BEHAN, a citizen of the United States, residing at Lapeer, in the county of Lapeer and State of Michigan, have invented certain new and useful Improvements in Cattle-Guards, of which the following is a specification, reference being had thereto in to the accompanying drawings.

The invention relates to railway cattle-guards of a type in which wood and metal are combined in the construction.

In the earlier construction of railway cattle-guards the bars were formed from wood. These guards while satisfactory in many ways were open to the objection that the ends of the bars would frequently check and split or would rot away through the action of the elements. Later in development metallic guards were substituted for the wooden ones. These while possessing greater strength when first placed have not proven to have longer life. One reason for this is that in the passage of refrigerator-cars over the road the drippings of salt water cause rapid corrosion of the metal guards, so that they are soon weakened and broken.

It is the object of the present invention to combine the advantages and to avoid the faults of both the wooden and the metal guards; and to this end the invention consists, first, in the peculiar construction of a guard in which edged wooden bars are used for destroying the foothold and metallic bars are employed for supporting said bars and protecting the ends thereof.

The invention further consists in the peculiar construction of said metallic supporting bars and, further, in the peculiar construction, arrangement, and combination of parts, as hereinafter set forth.

In the drawings, Figure 1 is a perspective view of one of the metallic supporting members, showing a wooden rail engaged therewith. Fig. 2 is a perspective view of the center support for the rails. Fig. 3 is a longitudinal section, and Fig. 4 is a cross-section of the guard.

A represents wooden rails which are tapered

to an edge at the top, so as to destroy the foothold of the animal attempting to cross the guard. These rails A are formed of suitable length and are preferably supported at the center by a strip B, which, as shown, is formed of a notched bar. The ends of the rails are supported by metallic members C.

The members C are preferably formed from sheet metal struck up to have a horizontal securing-flange *a*, an upwardly-inclined portion *b*, and a downwardly and substantially vertical portion *c*. The portion *c* has a series of apertures *d* formed therein, each adapted to receive one of the rails A. The metal which is struck out in forming these apertures is bent inward from the lower edge of said aperture and forms a supporting-shelf *e*, upon which the rails A may rest.

When placed upon the track, the members C are secured to cross-ties, and the bars A are then engaged therewith, supported upon the shelves *e* and the bar B, being held a short distance above the ties in the road-bed.

It is desirable that the upper edges of the bars A should be substantially at the height of the steel rails. At the same time the effectiveness of the guard is increased by reducing the thickness or depth of the rails A, as they are thus rendered more flexible, which further destroys the foothold of the animal. With my construction bars of less height than the steel rails may be used, and as they are supported above the ties upon the shelves *e* their upper edges will be equal in height to said rails. A double advantage results from this: First, less material is used, and, second, their effectiveness as a foothold-destroying medium is increased.

In addition to the function of supporting the bars A the members C form a cap for the ends of the bars, which protects them from the action of the elements and prevents checking or rotting. Another advantage of the construction is that the member C may be skewed in relation to the bars A, so that for an angle-crossing the bars A may be arranged parallel with the track and the members C parallel with the crossing road.

What I claim as my invention is—

1. A railway cattle-guard comprising a series of edged bars, a metallic end member forming a support for said bars, said member being apertured to receive the ends of said bars and a supporting-shelf formed by the metal struck out from each aperture.
2. A cattle-guard comprising a series of bars and metallic end caps provided with apertures designed to receive the ends of said bars, and supporting-shelves adjacent said apertures affording rests for the ends of the bars.

3. In a railway cattle-guard, the combination with a series of bars, of a metallic end cap apertured to receive the ends of said bars, and the metal struck out from said apertures being turned inward to form supporting-shelves within the metallic end cap for the ends of the bars. 15 20

In testimony whereof I affix my signature in presence of two witnesses.

CHRISTOPHER BEHAN.
